UNITED STATES PATENT OFFICE.

JOHN C. FOX, OF MANSFIELD, OHIO, ASSIGNOR TO WESTINGHOUSE ELECTRIC PRODUCTS COMPANY, A CORPORATION OF MICHIGAN.

RIMMING MACHINE.

Application filed March 1, 1923. Serial No. 622,106.

My invention relates to material removing devices and particularly to rimming machines.

The object of my invention is to provide a relatively simple, compact and easily operable device for rimming sheet-metal plates.

In the manufacture of enameled sheet-metal plates, it frequently becomes necessary to remove a portion of the material spread upon the plate before it is placed within a furnace in order that an edge portion of the plate may have the powdered enamelling material removed therefrom and my invention has for its object to provide a device to effect this operation.

In practicing my invention, I provide a skeleton frame on which is mounted a vertically adjustable track frame upon which is located a reciprocally movable work-supporting table. A rear stop and a guard member are mounted on the work-supporting table, the rear stop and the guard members being adjustable laterally of the table and the guard being adjustable also in a vertical direction. A pair of rotatable circular brushes are provided, one being mounted on a horizontal shaft and the other on a vertical shaft, suitable driving means being provided therefor.

In the drawings:—

Figure 1 is a view, in side elevation, of a device embodying my invention,

Fig. 2 is a top plan view thereof,

Fig. 3 is an end view thereof, and

Fig. 4 is a fragmentary view, in end elevation, of the protecting edge member comprising a part of the device embodying my invention.

A skeleton frame 10 comprises a plurality of vertically extending metal members 11 tied together by a plurality of diagonal metal bars 12 to stiffen the structure. Angle-bar members 13 extend longitudinally of the frame work at each side thereof and are suitably secured to the upper end of the vertically extending members 11. Laterally and diagonally extending metal bars 14 are provided at each end of the skeleton frame to brace it in a lateral direction.

A track frame supported by the skeleton frame 10 hereinbefore described, comprises a pair of longitudinally extending angle-bar members 15 which are secured, at their ends, to laterally extending cross-bars 16. The track frame is adjustably mounted on the

members 13 by a plurality of link members 17 which are pivotally connected to the respective members 13 and 15 and provide, in effect, a parallel alinement between the track frame and the supporting skeleton frame 60 therebeneath.

The intermediate members 17 are respectively provided with an integral depending portion 18, the lower ends of which are connected by a laterally extending rod 19. 65 Means for varying the position of the track frame relatively to the skeleton frame comprises a longitudinally extending rod 21, which is provided, at one end, with a hand wheel 22 suitably secured thereto and, at its other end, with a screw-threaded portion 23 which is located in a suitable screw-threaded opening 24 in the member 19. The outer end of the rod 21 immediately adjacent the hand wheel 22, is rotatably located in a bearing member 25, so that upon rotation of the rod 21 by the hand wheel 22, the laterally extending rod 19 is moved longitudinally of the skeleton frame and varies the angular position of the members 17 whereby a vertical movement of the track frame is effected. It is, of course, understood that the track frame is also moved in a longitudinal direction but the extent of this movement is relatively small and is of no effect in the 85 operation of the device.

Wearing strips 26 are suitably secured to the upper surface of the horizontally extending web of the angle bars 15 and may comprise a suitable hardened material in order 90 to withstand the wear to which it is subjected during the operation of the device.

A work-supporting means comprises a substantially rectangular metal frame 27 upon which is located a sheet-metal plate 28, suitably secured thereto. A plurality of flanged wheels or rollers 29 are provided at each side of the work-supporting means and rest upon the wearing strips 26 to permit of moving the work-supporting means reciprocally and longitudinally of the skeleton frame. A flat metal strip 31 is suitably secured at one side of the work-supporting means, and an adjustable rear stop 32 is provided intermediate the back stop 31 and the other side edge of the work-supporting means.

A protecting-edge member 33 comprises a pair of vertically extending metal members 34 each of which is suitably shaped at its 110

lower end to engage the laterally extending part of the frame 27 of the work-supporting means and is provided with a laterally and horizontally extending portion 35 which may 5 be clamped against the member 27 to securely lock the two parts of the protecting edge device in any predetermined position relatively to the work-supporting means. A plurality of spaced slots 36 and 37 are provided in the member 27, and thumb nuts 38 are provided on suitable bolts operatively engaging the members 35 to permit of clamping them tightly against the member 27 in any desired position. The member 34 is provided, at its upper end, with a laterally extending slotted portion 39 within which is rotatably mounted an adjusting nut 41 which operatively engages the upper screw threaded end of a link 42, which is secured, at its 10 lower end, to a vertically movable shoe 43, which operatively engages one side of the member 34. A bolt 44 and a nut 45 serve to connect the lower end of the link 42 to the shoe 43 and, by extending through a suitable slot 46 in the member 34, permit also of holding the shoe 43 in its proper operative position against the outer face of the member 34 and of securing the shoe tightly 15 against the member 34 in any predetermined position.

A guard 47 comprises a longitudinally extending metal bar having an outer beveled edge. At each end of the member 47 there is provided an arm 48 suitably secured thereto, which is pivotally mounted in the bolts 44 intermediate its ends and has a handle 49 secured to the other end thereof in order to permit the operator to raise the guard 47 from the work-supporting means.

40 A horizontally extending shaft 51 is located in suitable bearing members 52 and carries, at its outer end, a substantially circular brush 53 suitably secured thereon. A pulley 54, mounted on the shaft 51 between the two bearing members 52, permits of driving the shaft and rotating the brush by a suitable electric motor 55. A vertically extending shaft 56 is located in suitable bearings, (not shown) and carries, at its upper 45 end, a substantially circular brush 57. The shaft 56 is driven by suitable means not shown by the motor 55. As the particular type of drive may be of any suitable or desired kind and forms no particular part of my invention, it is not further illustrated and described. The motor and belts may be mounted in a suitable box or casing 58 which supports the shafts 51 and 56 and the bearing members.

50 The sheet metal plates which it is desired to enamel are covered on their upper surface with a relatively thin layer of enamelling powder and when it is necessary to remove edge portions, or strips of this material, a sheet-metal plate 59 is placed upon the upper

surface of the work-supporting means with its rear edge in operative engagement with the rear stop 32 which has been so adjusted relatively to the front beveled edge of the guard member 47 and of the brush 53 that 50 the proper width of the edge strip of powder is removed by the rotating brush 53 when the work-supporting means is moved longitudinally of the skeleton frame. Any desired width of edge strip may be removed 55 from any sheet-metal plate, it being only necessary to suitably adjust the rear stop 32, as may easily be done by the holding screws, provided in and extending through the member 32. The guard member is made adjustable laterally and vertically of the work-supporting means in order to take care of any wear of the various parts of the device and also to correct any inaccuracies in the manufacture or assembly of the parts of the 60 complete machine.

If it is desired to remove material not only from the flat face of a sheet metal plate but also from a depending edge portion, the vertically extending shaft 56 and the brush 57 mounted thereon may be used and the brush 57 will be effective to remove the material from the vertically extending portion of the sheet metal plate, as will be easily understood.

The device embodying my invention thus provides a relatively simple and inexpensive means for removing material from the edges of sheet-metal plates preparatory to placing them in a heated oven to enamel them, the 100 work-supporting means being manually and reciprocally movable of the track frame to cause the entire length of the sheet-metal plates to be subjected to the action of the respective brushes.

105 Various modifications and changes may be made without departing from the spirit and scope of the invention, and I desire, therefore, that only such limitations shall be imposed thereon as are indicated in the appended claims.

110 I claim as my invention:—

1. In a rimming machine, in combination, a horizontally extending rotatable shaft, a circular brush mounted at one end of said shaft and rotatable therewith, a vertically extending rotatable shaft, a circular brush secured thereto, and reciprocally movable means for supporting material to be operated on by both said brushes simultaneously. 115

2. In a rimming machine, in combination, a horizontally extending rotatable shaft, a circular brush mounted at one end of said shaft and rotatable therewith, a vertically extending rotatable shaft, a circular brush secured thereto, reciprocally movable means for supporting material to be operated on by both said brushes simultaneously, and means for permitting the adjustment of material 125 relatively to both of said brushes. 130

3. In a rimming machine, in combination, a rotatable brush, a reciprocally movable means for supporting material to be operated on by said brush, and adjustable means on said supporting means for holding material thereagainst and for permitting said brush to operatively engage said material over a predetermined edge portion only. 5
4. In a rimming machine, in combination, a rotatable brush, a reciprocally movable means for supporting material to be operated on by said brush, and a tilttable guard member mounted on said material-supporting means. 10
5. In a rimming machine, in combination, a rotatable brush, a reciprocally movable means for supporting material to be operated on by said brush, and a tilttable guard member mounted on said material-supporting means. 15
6. In a rimming machine, in combination, a rotatable brush, a reciprocally movable means for supporting material to be operated on by said brush, an adjustable rear-stop member on said supporting means for positioning the material laterally of said brush and an adjustable and tilttable guard member on said material-supporting means for holding down one side of the sheet-material being operated on and for permitting said brush to operatively engage a predetermined portion only of said material. 20 25 30

In testimony whereof, I have hereunto subscribed my name this 19th day of February, 1923.

JOHN C. FOX.
